UNITED STATES PATENT OFFICE

169,021

EARRING OR SIMILAR ARTICLE

Edward White and Rodney H. Witmer,
Miami, Fla.

Application August 13, 1952, Serial No. 21,021

Term of patent 3½ years

(Cl. D45—9)

To all whom it may concern:

Be it known that we, Edward White and Rodney H. Witmer, citizens of the United States of America, residing in Miami, county of Dade and State of Florida, have invented a new, original, and ornamental Design for an Earring or Similar Article, of which the following is a specification, reference being had to the accompanying drawing, forming a part thereof.

Fig. 1 is a plan view of an earring or similar article showing our new design.

Fig. 2 is an edge view thereof.

We claim:

The ornamental design for an earring or similar article, substantially as shown.

EDWARD WHITE.
RODNEY H. WITMER.
